UNITED STATES PATENT OFFICE.

JOHN WIRTH, OF NEW YORK, N. Y.

SHAMPOOING AND HAIR-WASHING APPARATUS.

Application filed August 24, 1922. Serial No. 583,972.

To all whom it may concern:

Be it known that I, JOHN WIRTH, a citizen of the Republic of Austria, residing at New York, in the county of New York and State of New York, have invented certain new and useful Improvements in Shampooing and Hair-Washing Apparatus, of which the following is a specification.

This invention relates to improvements in 10 barber's appliances; the principal object being to construct a device for shampooing, massaging and cleaning the scalp, removing dandruff from the head, and invigorating the papillæ of the hair.

16 A second object is to provide a device of the character described, which obviates and dispenses with an attendant's help for operation, making it therefore adapted to be used with equal advantage by the professional 20 barber, who with the help of such apparatus can accommodate several customers at the same time, as well as by an individual in the bath- or dressing-room at home.

A third object is to provide a mechanical 25 device which overcomes the many drawbacks and dangers, attendant upon the old manual method of shampooing or massaging the scalp, and concerning personal comfort and sanity, as for instance, casual injuries of the scalp and, perchance, consequent infections through unclean finger 30 nails, the flooding of the eyes and face with soapsuds, or bespattering and staining the clothes with it.

35 A fourth object is to provide means for operating such device, as forms the subject of the invention, which are entirely within the manual control and discretion of the person under treatment, as many nervous or captious people rather unwillingly submit to being handled bodily by others.

A fifth object concerns the economical 45 consumption and application of the liquid use for shampooing purposes by providing an attachment which, though capable of holding a large supply of said liquids, only yields it in predetermined and adjustable smaller quantities, every time the supply is tapped for application. Other and minor 50 objects will become apparent by the detailed description of the invention.

An apparatus in accordance with my invention comprises a "rotatable and detachable brush", a "manually driven mechanism", to which said brush is coupled, a "container" for the liquid soap or shampoo,

with its "adjustable supply mechanism", a "rubber hood" for the protection of the eyes, face, and neck during the procedure, a "safety guard" for the scalp, a "water supply pipe with spray nozzle", and the necessary "frame work" supporting these various appliances.

All the above named objects are attained by means of the apparatus and appliances 60 shown in the drawings in which, Fig. 1 is a vertical middle section through the apparatus, though showing the piping and the liquid cup in full.

Fig. 2 shows a front view of this apparatus drawn to smaller scale and its installation over a wash basin.

Fig. 3 is a front view of the rotatable brush, shown in section in Fig. 1, after the safety guard and the rubber hood has been 75 removed.

Fig. 4 illustrates an apparatus employing a modified driving mechanism.

Fig. 5 is a detailed sectional view of the container for the liquid soap or shampooing 80 mixture.

Fig. 6 is a sectional view taken on line 6—6 of Figure 4.

In the construction illustrated in Fig. 1 numeral 10 represents a wall-chest, preferably of wood, built in the shape of a triangular overhanging bracket-closet, substantially closed on all sides, as shown.

The front cover consists of at least two boards, 10^a and 10^b, butt-joined together along a horizontal line 10', with a semi-circular cutout in each board, which, joined together, form a circular opening for the insertion of a flanged split-bushing 11, made of bronze or any antifrictional material.

The flange 11^a is supported on and fastened to the inside of the front boards by a set of woodscrews 11^b, but the split line of the bushing should not coincide with the buttjoint of the frontboards.

Along the vertical middle line of the rear cover 10^c, on the inside of the chest the water supply pipe run 12 is installed, passing through adequate openings in the lower portion of the front board 10^a and the rear portion of the top cover 10^d. In addition to these entrance and exit-openings, guiding the piping, the latter may be fastened more securely to the rear board by a pipe bracket 12^a. The wall chest itself is fastened to the wall 13 in any convenient way, not detailed in the drawing; it may be hung

from the top by means of a pair of eyelets and wall hooks, or the rear board may be furnished with a projecting flange on either vertical side, serving as a nailing strip or screw ledge. Below the entrance of the supply pipe into the wall chest is provided a shut-off valve or cock 14 and the pipe run terminates on top in a reversed Y-shaped fitting 15. This fitting is plugged up on 10 the run, where it passes through the top-cover 10^d by a pipe plug 15^a, and this arrangement gives a convenient access to the main run as well as to the branch outlet 15' for cleaning, or the run may be continued 15 here for further supply purposes.

Into the branch outlet 15' is screwed the pipe-end 16, which, as Fig. 1 shows, thus comes into alignment with the center line of the bushing 11.

20 Over this stationary inclined pipe is slipped a rotatable sleeve 17 of peculiar construction. Although shown in the drawing as consisting of one integral casting, it may be made up in practice by several parts combined into one structural member. The main body of the sleeve consists of a cylindrical mantle 17^a, studded with short pegs or teeth 17^{a'}. This studded mantle is confined within two flanges 17^b and 17^c, the latter being seated on the flange 11^a of the bushing 11. Below the flange 17^c the sleeve passes through the bushing and expands into the conically shaped dish 17^d.

30 Into the cavity of this dish is detachably mounted the circular brush 18. At three places along its periphery, spaced 60° apart, the dished member 17^d is furnished with a slot 17^e; and registering with these slots there are provided three clips 19, screwed 40 into the brush pad 18^b. These clips are tapering pins with a slotted buttonhead and a few tapered screw threads on the shank just below the head. When they are fastened in place on the brush pad with their buttonhead on the bristle-side, their ends, projecting on the backside, are bent over at right angles, leaving just enough of the projecting shank straight, to fit the rim of the dished bowl 17^d between the bent-over prong 19' and the backside of the brush pad 18^b.

When the clips are turned in their threaded seats so that the prongs point in a centrifugal direction, the brush with the three clips can be slipped into place, the shanks of 55 the clips fitting into slots 17^e. Giving each clip a turn of about 90° or 180° will securely attach the brush pad to the dish, respectively the sleeve 17.

60 The stationary pipe 16 after passing loosely through the sleeve, terminates in a spray nozzle or cap 20, which can be made integral with or detachable from the pipe 16.

65 This cap has the shape of a truncated cone made of perforated sheet metal. While the spray perforations in the flattened por-

tion 20^a, at the end, are rather fine, so as not to let out much water, the holes on the conical side portion 20^b are somewhat larger, so that the greater quantity of the liquid is distributed in a centrifugal direction. The 70 bristles 18^a, set in groups and normally to the inner side of the conical brush pad, would of course all converge toward the axis of the cone, and their free ends are clipped off to form a cavity 18'; semispherical or 75 nearly so. The general contour of the brush-inside will therefore conform to that of the scalp.

At two suitable points, opposite to each other, in the upper portions of the side walls 80 10^a, two longitudinal slots 10^f are provided respectively and, running parallel with these slots on the outside of the chest, are journaled in little brackets 25' two flanged idler rollers 25.

85 A leather belt 26, with a handle 26' at each end, is placed from the underside around the studded sleeve, passed through the slots 10^f and over the idlers 25.

90 The middle portion of the belt is provided for a considerable and sufficient length with perforations, into which the pegs or teeth 17^{a'} of the sleeve must fit, when the latter 95 rotatingly engages with the belt; and the slots must be cut at such an angle that the free ends of the belt will hang down vertically, as shown in Fig. 1. It will be evident from the description, that, when the belt handles are alternately pulled downwards, the sleeve and the brush, attached to its end, 100 will be given a vigorous alternating, rotary movement.

95 Fixedly attached to the front boards 10^a, 10^b and encasing the rotatable brush with as little clearance as feasible, is provided a 105 funnel-shaped housing 27, formed with an outer flange 27^a around its narrow opening, furnished with bolt holes and hexagon bolts 27' for fastening the housing to the wall chest front and with an inner flange 27^b 110 around the wider opening. Fastened to the latter flange and extending inwardly toward the brush periphery, is arranged a flat annular rubber gasket 28 of rather substantial thickness, but resilient enough to yield 115 somewhat to pressure. This serves as a safety guard to prevent a too forceful and sudden insertion of the skull into the brush which might result in injuries to the scalp by prominent working parts of the apparatus.

120 On top of this rubber gasket is provided a hood 29 of elastic, soft, yet waterproof material, like rubber or the like. If made of rubber, the opening 29' must be narrow enough that, when expanded and stripped over the head, down to the neck, the ears and the eyebrows, it forms a waterproof joint. If made of other material, an elastic and contractible string must be provided 125 around said opening. The upper rim 29'' 130

of the hood can conveniently be fastened together with the outer gasket rim to the housing flange 27^b. At the lowest point of the housing a water outlet nipple 30 with a rubber hose 31 attached to it, is provided, (see also Figs. 2 and 3). This rubber hose can be led into a wash basin or sink 32 or may drain into any other suitable receptacle.

A modification of the rotating means for 10 the brush is shown in Fig. 4, which, like Fig. 1, shows the wall chest also in section, but the rest of the apparatus in full view, with the brush parts indicated by dotted lines only.

15 Instead of the belt 26 a chord or rope 35 is employed. The sleeve 36 on the pipe run 16 is similar to the one, described before, but the mantle 36^a between the flanges 36^b and 36^c is smooth, instead of being studded with 20 pegs, and to its centre is fastened by a staple 36^f or in any other suitable manner the rope 35 at half of its total length. One of the rope ends is wound up around the mantle to within the flange 36^b, and both ends are 25 hung downwards over two idlers 37, and 37', rotatably mounted on the axle 37^a, see Fig. 6.

The idler axle is fixedly supported in the wall chest side boards 10^e and the idlers 30 must be so proportioned and situated that the rope ends are kept approximately in vertical planes, tangential to the mantle 36^a. The short pipe ends 37^b, 37^c, and 37^d serve 35 as separators for properly spacing the idlers apart.

The free rope ends are led through slots 38 and 38', in the front board 10^a; and these 40 slots are cut out sufficiently at the top to permit the rope ends to be pulled or swung towards the front, as indicated by 38^a, and the dotted arcs 39, so as to be within convenient reach of the person using the apparatus. The two rings 40 and 40', coupled to the 45 ends of the rope, serve as handles. The function of this rope is analogous to that of the belt, described above, and the arrows 41 indicate the alternating motions for imparting rotary reciprocating movement to the sleeve 36 and brush 18. It is understood 50 that this rotary movement results from the alternating winding up and unwinding of the two rope ends from the middle, where they meet underneath the staple 36^f toward the flanges 36^b and 36^c respectively.

55 It remains to describe the means by which the shampooing fluid, consisting of liquid soap or other suitable mixtures is provided and distributed over the brush during the operation. On top of the funnel shaped 60 housing 27 and preferably integral with it, is provided an annular saddle 45 which has a concentric hole 45^a, reaching through the shell of the housing. On top of this saddle is mounted by tap bolts 46 the cylindrical 65 container 47, comprising the bottom piece

47^a, formed as an annular flange bolted unto the saddle, having a short dished neck piece, threaded on the outside, 47^b and a threaded throat 45^{a'} in alignment with the hole 45^a, see Fig. 5.

70 The container further comprises the mantle or side wall 48 and the cover 49. This cover is shown as a dished lid, threaded on the inside, so as to be screwed tight upon the top of the mantle. This mantle 48, which 75 may be made of glass, so as to show the level of the liquid contents, has on the outside of the top rim, as well as on the inside of the bottom rim threads provided, corresponding to the threads of the cover and the bottom 80 piece. These threads, 49^b and 47^b respectively, should be rather coarse, if the mantle is made of glass; and in this case it would be advisable to provide also a rubber washer 47^d, upon which the mantle can be screwed 85 down tight. The cover 49 has a neck 49^a, on which is fastened the nipple 50^a of a rubber ball 50.

90 On top of the front board 10^d of the wall chest is provided a bracket 51, bolted on or otherwise fastened. This bracket terminates in a fulcrum pin 51^a, on which is hinged the flap 52, see Figs. 2 and 5. To this latter piece is fastened the one-armed lever 53. From the end of the lever the 95 chain 54 with the chain handle 55 is hung in such fashion that the latter is within convenient reach of the person, manipulating the apparatus. The pointed and perforated knee-nozzle 56, screwed into the bottom opening 45^a, completes the supply-device for the shampooing liquid.

100 It is evident that whenever the chain is pulled, the one-armed lever compresses the rubber ball, which in turn drives out a certain amount of the liquid contents by the compressed air through the pointed nozzle and squirts it forcibly against and into the bristles of the rotating brush. The mixing 105 with the water and the rotating motion of the brush distributes it over the scalp. The size of the rubber ball determines the quantity 110 of the liquid dose to be supplied by one tapping.

115 The last described construction of the shampooing supply device is of course subject to many changes and modifications, as there are a number of syphons and priming valves in the market which would fulfill the function required in a great many similar ways and it is understood that the invention proper is not confined to the use of the described pneumatic squirting device.

120 The method of operating the invention is as follows: The person using the apparatus 125 stands in front of it, facing the wall chest. He inserts his head into the rubber hood, adjusting it well over the front head, temples, ears and nape of the neck, then he turns on the water in the supply pipe 12,

and agitates the brush by moving the handles alternately up and down. Meanwhile he presses his head rather close against the safety rubber gasket 28, turning it also sideways to thoroughly wet his hair. Then, after turning off the water, he gives a pull to the chain on his right side which operates the shampooing supply device. By renewed agitation of the brush he distributes the soap or shampoo through the hair and after sufficient massaging of the scalp with the brush, he turns on the water supply once more, rinsing the soap or shampoo-liquid out of the hair. The waste water is drained off simultaneously through the hose 31 into the sink 32.

After the water is shut off and a few more turns with the brush are given, to squeeze the superfluous water out of the wet hair, the person withdraws the head from the hood and dries the hair with a towel or may use any of the provided means for finishing the operation.

The foregoing description is believed sufficiently clear to enable those versed in the art to make and use the device described, but it is understood that the execution admits of many modifications without deviating from the main principles of the invention.

Having thus described my invention, what I claim as new and desire to secure by Letters Patent is:

1. A shampooing apparatus for the scalp comprising a water supply pipe, a conical-shaped brush rotatably and axially mounted on the supply end of said pipe, means to rotate the brush and means to supply shampooing liquid to said brush.

2. A shampooing apparatus for the scalp comprising a water supply pipe, terminating in a spray nozzle, conical-shaped brush rotatably and axially mounted on the pipe in such manner that the brush surrounds the nozzle, means to impart a rotary alternating motion to said brush and means to supply shampooing liquid to said brush.

3. A shampooing and hair washing apparatus, comprising a conical brush, shaped on its face approximately to the contour of the scalp, a stationary support on which this brush is rotatably mounted, means to impart a rotary alternating motion to said brush and means to supply liquid to the inside of the brush.

4. A shampooing and hair washing apparatus, comprising a water supply pipe, a conical-shaped detachable brush, shaped on its face approximately to the contour of the scalp, a stationary structure supporting and encasing the brush around its periphery, means to rotate said brush, a resilient compressible container, supported on said structure, to supply shampooing liquid, means to manually operate said container and means to mix the shampooing liquid, supplied by the container, intimately with the water, provided by the water supply pipe.

5. A shampooing and hair washing apparatus, comprising a stationary water spray pipe, fixedly supported in an inclined descending position, a rotary member, axially mounted on said pipe, and terminating in a circular flange-shaped part at its lower end, said rotary member being so formed as not to obstruct the spraying portion of said water pipe, a flexible tractive element, adapted to engage said rotary member by friction and impart to it a rotary motion, means to manually actuate said element, a circular brush, detachably mounted on the circular flange-shaped part of said rotary member and surrounding the spraying portion of the water pipe, and means to supply ingredients adapted to mix and dissolve in the spray water to said rotary brush.

6. A shampooing and hair washing apparatus, comprising a water supply pipe, a detachable rotary brush, a rotary member, mounted on said pipe, a clamping device to attach said brush in axial alignment with and to said rotary member, means to impart rotary motion to said member and brush, a stationary funnel-shaped housing encasing the rotary brush, but not obstructing the operating surface of the same, means to support said housing, and a waterproof elastic hood attached to the housing and adapted to be adjusted over and to surround the scalp of a human head, forming a waterproof elastic joint along the base of the same.

In testimony whereof, I have signed my name to this specification in the presence of two subscribing witnesses, this 8th day of August 1922.

JOHN WIRTH.
